Primary Examiner — Keli L Hill*Assistant Examiner* — Sara S Sahneh(74) *Attorney, Agent, or Firm* — Goldstein Law Offices, P.C.**CLAIM**

The ornamental design for a gripping tool, as shown and described.

DESCRIPTION

FIG. 1 is a perspective view of the gripping tool in full lines.

FIG. 2 is a left side elevational view of the gripping tool.

FIG. 3 is a right side elevational view thereof.

FIG. 4 is a front elevational view thereof.

FIG. 5 is a rear elevational view thereof.

FIG. 6 is a top plan view thereof; and,

FIG. 7 is a bottom plan view thereof.
